[57] CLAIM

The ornamental design for a golf putter face design, as shown and described.

DESCRIPTION

FIG. 1 is a front elevational view of the golf putter face design showing our new design; and,
FIG. 2 is a front elevational view of a second embodiment of the golf putter face design as disclosed in FIG. 1.
The broken line showing of a golf putter head is for illustrative purposes only and forms no part of the claimed design.
